UNITED STATES PATENT OFFICE.

FRANCIS TEMPLE PAGE, OF PENSHURST, NEW ZEALAND.

WIRE-GRIP.

SPECIFICATION forming part of Letters Patent No. 696,260, dated March 25, 1902.

Application filed June 7, 1901. Serial No. 63,633. (No model.)

To all whom it may concern:

Be it known that I, FRANCIS TEMPLE PAGE, a subject of the King of Great Britain, residing at Penshurst, Pahiatua, New Zealand, 5 have invented a new and useful Improvement in Wire-Grips; and I do hereby declare the following to be a full, clear, and exact description of the same.

The grip for holding the wires of wire fencing while they are being strained that forms the subject of this invention has been specially designed for use in conjunction with wire-straining appliances and for any other form of appliances in which a gripping action 15 upon a wire is desired.

The grip consists of two oblong or other suitably-shaped pieces of metal one end of each of which is articulated to one of the arms of a pair of spring lever-arms that converge 20 together and are joined at their other ends. To this end is secured the straining chain or cable. The other ends of the oblong-shaped pieces of metal are slightly twisted in reverse directions and have both of their sides slit 25 for a short distance by parallel diagonal slots. The triangular pieces thus formed are turned up on one of the oblong pieces and down upon the other, so that when one piece is placed upon the other the triangular projections 30 upon one will engage with and pass beneath the triangular projections upon the other, while the diagonal portions upon each oblong piece of metal shall lie with their faces together. The wire to be gripped and strained 35 is laid across one of the oblong pieces and passed beneath the triangular projections upon each edge. The other oblong piece is then placed above its fellow and the edges of its triangular projections caused to loosely 40 grip the wire between them and the edges of the projections upon the first oblong piece.

In the accompanying drawings, Figure 1 is a side elevation of the appliances open. Fig. 2 is an end elevation of the same. Fig. 3 is a 45 side elevation of the appliances in the gripping position.

A B are the two oblong or other suitably-shaped pieces of metal, which are slightly curved in reverse directions. Each of the 50 pieces A and B are slit diagonally on both edges, as at a a and b b, and the triangular portions thus formed are turned down on A

and up on B, as shown in Fig. 2. The other ends of the pieces A and B are articulated at the points C and D to the spring-arms E, which 55 are joined together at their other ends and threaded through the end link of the chain F, which is connected to the straining appliance and upon which the straining pull is exerted.

The wire G to be strained is laid across the piece B and placed beneath the triangular pieces J on both sides. The other piece A is then turned around on its pivot C and placed above the piece B in such a manner that its 65 triangular pieces H shall project underneath the triangular pieces J upon the other oblong piece B. The wire G will thus be held between the triangular pieces on both the gripping-pieces A and B and will be gripped between the faces of the diagonal portions thereof. As a pulling strain is exerted upon the chain F the gripping-surfaces will grip harder upon the wire, and the stronger the pull the greater will be the amount of grip. 70 In some cases it might be advisable to shorten the gripping leverage upon the wires being strained, in which case the arms E will be removed from the holes C and D and inserted in the auxiliary holes C' and D'. When the 75 wire has been strained to the necessary degree and secured, the pull upon the chain F is removed, when the grippers will loosen their hold upon it, so that they may be removed therefrom by disengaging the triangular pieces H and J from contact with each other.

Although I have shown the gripping-pieces A and B of oblong shape, it will be understood that they may be made of any other form 80 without departing from the principle of the invention.

What I claim as my invention, and desire to secure by Letters Patent, is—

1. In gripping appliances for use with wire-straining apparatus, a pair of gripping-pieces that are each loosely articulated upon one of the arms of a pair of spring lever-arms, one of such gripping-pieces being formed with turned-down triangular portions upon its 95 edges, while the other gripping-piece is formed with correspondingly turned-up portions, as and for the purposes herein set forth.

2. In a wire-straining device the combina-

tion of a pair of gripping-pieces adapted for conjoint use as described, one formed with downturned angular projections on two opposite edges and the other with upturned angular projections on its corresponding opposite edges, and a pair of pulling-arms E on which the said gripping-pieces are respectively articulated, substantially as set forth.

3. The combination of the gripping member A formed with downturned angular projections a, a on two opposite edges and a plurality of pulling-holes C, C' at different distances from one end; the corresponding gripping member B formed with upturned angular pro-

jections b, b, on its opposite edges and 15 a plurality of pulling-holes D, D'; and the pulling device E having a pair of arms adapted to be hooked in either pair of pulling-holes C, D, or C', D', so as to cause the members A, B, to grip the wire with variable force, substantially as described.

In testimony whereof I have signed this specification in the presence of two subscribing witnesses.

FRANCIS TEMPLE PAGE.
